UNITED STATES PATENT OFFICE.

JOHN S. FINCH, OF BRIDGEPORT, CONNECTICUT, ASSIGNOR TO THE SINGER MANUFACTURING COMPANY, OF ELIZABETH, NEW JERSEY, A CORPORATION OF NEW JERSEY.

VARIABLE-SPEED POWER TRANSMITTER FOR SEWING MACHINES.

Application filed December 29, 1919. Serial No. 348,010.

To all whom it may concern:

Be it known that I, JOHN S. FINCH, a citizen of the United States, residing at Bridgeport, in the county of Fairfield and 5 State of Connecticut, have invented certain new and useful Improvements in Variable-Speed Power Transmitters for Sewing Machines, of which the following is a specification, reference being had therein to the accompanying drawings.

This invention relates to improvements in power-transmitters and particularly in power-transmitters for sewing machines employing a device for stopping the machine 10 in a predetermined position.

The primary object of the present invention is to provide a power-transmitter for sewing machines whereby the latter may be operated for an indefinite period at high speed and thereafter operated at low speed so that, at the time of operation of the stop-motion device, the machine may be stopped without substantially jarring the mechanism thereof. Another object of this invention is 25 to provide an improved power-transmitter for application to sewing machines generally.

The present invention also aims to improve the manually operated controlling means for this class of power-transmitters.

The present invention is designed as an improvement over the power-transmitter disclosed in U. S. patent to D. Noble, No. 1,001,674, dated August 29, 1911. In its preferred embodiment, a U-shaped hanger depends from the power-table supporting the sewing machine and sustains coaxially arranged driving and driven pulleys, of which the driving pulleys are rotated at relatively 30 low and high speeds. The driven pulley is secured upon an endwise movable shaft suitably journaled in the hanger and yieldingly urged in one direction to normally cause driving engagement between the low speed 35 pulley and the driven pulley, the latter of which is suitably connected by a belt with the sewing machine. In order to shift the driven pulley out of engagement with the low speed pulley and into engagement with the high speed pulley, there is provided a 40 rock-arm carrying a pulley-shifting cam and adapted to be actuated by an operating lever comprising a knee-shift.

The rock-arm is fulcrumed upon a crank-

pin projecting eccentrically from a rock- 55 shaft having an operating handle whereby the fulcrum of the rock-arm may be moved to shift the driven pulley-carrying shaft into an intermediate neutral position between the two driving pulleys. This movement of the rock-shaft positions the operating handle into the path of movement of the knee-shift, locking the latter against movement.

This power-transmitter is particularly 65 adapted for use in connection with a sewing machine such as is disclosed for instance in my U. S. Patent No. 1,394,075, issued October 18, 1921, wherein actuation of the knee-shift maintains the sewing machine in operation for an indefinite period, i. e., until the release of the knee-shift whereupon a mechanism is brought into action determining the number of stitches formed after the release of the knee-shift. At a predetermined 70 time after this mechanism is brought into action a stop-motion device operates to stop the machine in a predetermined position.

By employing the present power-transmitter in connection with the sewing machine, the release of the knee-shift causes the sewing machine to be driven at low speed at the time of operation of the stop-motion, thereby greatly reducing jarring of the operating 75 parts.

In the accompanying drawings, Fig. 1 is a view in front elevation and partly in section of the present improved power-transmitter for operating a sewing machine of 80 the character described. Fig. 2 is a right end elevation of the same. Fig. 3 is a longitudinal sectional view of the power-transmitter. Fig. 4 is a top plan view of the knee-shift and fulcrum-shift operating mechanism. Fig. 5 is a detail view substantially on the line 5—5, of Fig. 4, illustrating the device employed for limiting the movement 85 of the fulcrum-shift rock-shaft. Fig. 6 is a detail view of the mechanism brought into 90 action by the release of the knee-shift and determining the time of operation of the sewing machine after such release, and Fig. 7 a view in rear elevation of the machine 95 standard and of a portion of the overhanging arm.

Referring to the drawings, the present invention is employed in connection with a

sewing machine, supported on a power-table 1 and comprising a vertical standard 2 curving laterally into an overhanging bracket-arm 3 adapted to support and guide the needle or needle-carrying bar, presser-bar and the other operating parts (not shown) in the usual manner. Journaled in suitable bearings provided in the overhanging bracket-arm is the main actuating or driving shaft 4 of the sewing machine carrying at its outer end a fast pulley 5, a loose pulley 6 and a hand-wheel 7. A rock-shaft 8 is journaled in suitable bearings provided at the rear side of the overhanging bracket-arm and carries a crank-arm 9, connected by means of a rod 10 with one arm of a two-armed rock-lever 11 pivotally supported upon the machine frame by means of a pin 12 and normally urged to lift the rod 10 by means of the spring 13. The other arm of the lever 11 is adapted to be engaged by the flattened upper surface of a collar 14 carried by the upper end of a rod 15 rigidly secured upon an arm 16 projecting laterally from a swinging-frame 17.

The swinging-frame 17 is provided with oppositely disposed spaced ears, as 18, pivotally sustained by brackets as 19 depending from the table 1. Rigidly secured in the swinging-frame 17 is the horizontal portion of a rod 20 having a depending end upon which is secured a plate 21 adapted to be engaged by the knee of an operator to rock the swinging-frame 17, and thereby actuate the two-armed lever 11 causing a downward movement of the rod 10. This mechanism comprises a well known form of knee-shift for starting the operation of a sewing machine.

The rock-shaft 8 also carries a crank-arm 22 connected at its free end by means of a pivot-screw 23 with a link 24. The link 24 engages the screw 25 upon a laterally projecting arm 26 of the usual swinging frame 27 of a stop-motion device well known in the art. This stop-motion device comprises a plunger 28, carrying a collar 29 and embraced by a spring 30 interposed between a shoulder formed on the swinging-frame and the collar 29. Secured upon the shaft 4 adjacent the fast pulley 5 is a cam 31 formed with a stop-notch 32 adapted to be engaged by the end of the plunger 28 in the stopping position of the machine. An arm 33 of the swinging-frame 27 carries a stud 34 adapted to be engaged by the notch 35 of a latch-lever 36 pivotally supported by a fulcrum-pin 37 upon the frame of the machine. Also carried by the pin 37 is a trip-finger 38 adapted to be engaged by a flange 39 formed on the end of a sleeve 40 splined to the shaft 4 so as to rotate therewith but slidably longitudinally thereon. The sleeve 40 is provided with a worm 41 adapted to be engaged by a nut 42 secured by means of

a screw 43 upon an arm 44 suitably clamped upon a shaft 45. The shaft 45 is journaled in a suitable bracket provided on the rear side of the overhanging arm 3 and is surrounded by a coiled spring 46 acting to maintain an arm 47 carried by the shaft in contact with a cam 48 suitably secured upon the rock-shaft 8.

When the plate 21 is shifted to the right as viewed in Fig. 1, the rod 10 is moved downwardly as previously described thereby rocking the shaft 8 and through the link 24 swinging the frame 27, thereby causing the plunger 28 to be moved laterally out of the stop-notch 32 against the action of a spring 49. The rocking of the shaft 8 at the same time causes the arm 47 to ride the surface 48' of the cam 48, thereby lifting the nut 42 out of engagement with the worm 41. This permits a spring 50 interposed between a collar 50' secured upon the shaft 4 and the sleeve 40 to shift the latter to the right. This movement of the collar 40 releases the finger 38 from the flange 39 and permits the latch-lever 36 to engage the stud 34 to hold the swinging-frame 27 out of stopping position. This position of the parts may be maintained for an indefinite period, or in other words, so long as the knee-shift is engaged by the operator. When the plate 21 is released by the operator a spring 51 coiled about the shaft 8 causes a rocking movement of the latter in an opposite direction. This movement of the rock-shaft 8 permits the arm 47 to ride off the surface 48' of the cam 48 and under the action of the spring 46 causes the nut 42 to engage the rotating worm 41. Inasmuch as the nut 42 is held against endwise movement, the sleeve 40 is caused to move to the left as indicated in Fig. 1, thereby tripping the latch-lever 36 under the action of the flange 39 upon the finger 38. The swinging-frame 27 is now free to be actuated by the spring 49 whereupon the end of the plunger 28 rides the outer periphery of the cam 31 until it enters the notch 32 to stop the machine in a predetermined position. It will be observed, however, that between the time that the nut 42 is caused to engage the worm 41 and the time of stopping of the machine several stitches will be formed and it is during that time that the machine is driven by the low speed pulley of the power-transmitter about to be described.

The power-transmitter comprises a substantially U-shaped hanger 52, suitably secured to the under side of the table 1 and provided with bosses 53 and 54 affording bearing-supports for the transmitting mechanism. Secured in the boss 54 by means of a screw-bolt 55 is a bearing 56 closed at its outer end by a cap 57 suitably secured thereto. Secured within the bearing 56 by means

of a set-screw 58 is a bushing 59 provided on one end with a flange 60, upon which bushing is journaled the hub 61 of a high speed driving pulley 62. The hub 61 of this pulley bears at one end against the flange 60 and at its opposite end against a thrust-bearing comprising a ring 63 held in position by means of a split-ring 64 and in contact with a plurality of balls, as 65, within 5 an annular portion of a ring 66. The ring 66 is positioned in an annular recess 67 formed in the bearing 56. Journaled for endwise movement within the bushing 59 is a power-transmitting shaft 68 engaged at 10 one end by the conical end of a pintle 69 of which the outer end projects through an aperture in the cap 57. A coil-spring 70, interposed between the cap 57 and a shoulder on the pintle 69, acts to normally force the 15 shaft 68 endwise in the bushing 59 and to the left as viewed in Fig. 3.

Secured upon the shaft 68 by means of the screw 71 is the hub of a driven pulley 72 provided on opposite faces with friction 20 rings 73 and 74. On the side of the driven pulley 72 opposite to that of the high speed pulley 62 is a low speed pulley 75, the hub 76 of which is journaled upon a bushing 77 secured by a screw 78 within a bearing 79 25 secured within the boss 53 by means of a screw-bolt 80. The end thrust of the pulley 75 is taken up in the same manner as that described in connection with pulley 62 and need not therefore be further detailed. The 30 driven pulley 72 in the stopping position of the sewing machine is connected by means of a belt 81 with the loose pulley 6. This belt 81 is adapted to be shifted by means of a fork 82, carried by the swinging frame 27, 35 upon the fast-pulley 5 to start the operation of the sewing machine. The driving pulleys 62 and 75 are respectively connected by means of belts 83 and 84 with pulleys 85 and 86 carried by the power-shaft 87. It will be 40 observed that the pulley 85 is considerably larger than the pulley 86 thereby rotating the pulley 62 at a considerably higher speed than that of the pulley 75. The friction ring 73 carried by the pulley 72 is adapted 45 to engage the face 88 of the pulley 75 and the friction-ring 74 is adapted to engage the face 89 of the pulley 62, these engagements occurring alternately when the shaft 68 is shifted endwise.

50 On its end opposite to that engaged by the pintle 69, the shaft 68 is engaged by the conical end of a pintle 90 formed with a slotted outer end affording a wall 91 engaged by a pulley-shifting cam 92 of a rock-arm 93. The hub 94 of the rock-arm 93 is journaled upon the shank 95 of a crank-pin comprising a shouldered screw 96 threaded eccentrically into the end of a rock-shaft 97. The rock-shaft 97 is journaled in a bracket 55 98 projecting laterally from a support 99 ad-

justably secured by means of a screw-bolt 100 within a boss 101 formed on the hanger 52. The rock-shaft 97 is limited in its movements by a pin 102 projecting from the bracket 98 and adapted to be engaged by 70 shoulders provided on diametrically opposite sides of a stop-element 103 preferably integral with the shaft 97. At its outer end there is suitably secured upon the rock-shaft 97 an operating crank 104 having a handle 75 105. It is evident that the shaft 97 may be turned substantially 180° by means of the crank 104. The crank-pin 96 in the positions illustrated in the several figures of the drawings is by this movement displaced laterally to cause the cam 92 of the rock-arm 93 to engage the pintle 90 and shift the shaft 68 endwise against the action of the spring 70 to position the driven pulley 72 intermediate the driving pulleys 62 and 75 and in disengaged relation with both of them. Consequently the crank-pin 96 forms a movable fulcrum for the rock-lever 93 and it is evident that by turning the rock-shaft 97 in the opposite direction, the spring 70 may 80 85 perform its normal function of maintaining the driven pulley 72 in engagement with the low speed pulley 75.

In order to shift the driven pulley into engagement with the high speed pulley 62, the 90 rock-arm 93 is provided with a fork 106 bridged by a pin 107 rotatably supported thereby. The pin 107 is provided with a transverse aperture entered by a rod 108 carrying collars, as 109, upon opposite sides 100 of the fork 106. The rod 108 is threaded into a boss 110 of a collar suitably secured upon the rod 20.

From the foregoing description, it will be 105 seen that movement of the swinging frame 17 to the right as viewed in Fig. 1 not only causes a shifting of the belt 81 from the loose pulley 6 to the fast pulley 5, a release of the stop-motion plunger 28 and a disengagement of the nut 42, but also causes a 110 shifting of the driven pulley 72 into driving engagement with the pulley 62 to rotate the machine at high speed through the consequent rocking of the lever 93 upon its fulcrum to cause engagement of the cam 92 115 with the pintle 90. When the knee-shift is released by the operator, the driven pulley 72 is immediately returned into engagement with the low speed pulley 75, but inasmuch as the sewing machine is operated for an 120 appreciable interval following the release of the knee-shift as previously described it is evident that the speed of the machine will correspond to the speed of the pulley 75 at the time the plunger 28 engages the notch 32 125 to stop the machine. Should it be desired to maintain the driven pulley in neutral position, the crank 104 is turned into the position indicated in the several figures of the drawings to shift the driven pulley in the 130

- manner previously described. However, this movement of the crank 104 placed it into the path of movement of the depending portion of the rod 20 thereby locking the knee-shift 21 against movement. The primary advantage derived from the locking of the knee-shift while the driven pulley is in neutral position is to prevent an operator from starting the machine while the driven pulley 10 is in this position. Without the provision of the locking device it would be possible to start the machine from neutral position and stop the same without first slowing the speed by contact with the low speed pulley.
15. Having thus set forth the nature of the invention, what I claim herein is:—
1. The combination with a sewing machine including a stop-motion device, automatic means for initiating a machine 20 arresting action of said stop-motion device, and a manually controlled device for determining the time of effective action of said automatic means at any point in the operation of the machine, of a power-transmitter 25 including a power-transmitting driven pulley, driving connections between said pulley and said sewing machine, relatively low and high speed driving pulleys adapted to be alternately placed in operative engagement with said driven pulley, and operative connections with said manually controlled device for relatively shifting said driving and driven pulleys to drive the sewing machine from said high speed pulley during 30 the period of ineffectiveness of said automatic means and from said low speed pulley during the time that said automatic means is effective.
  2. In a power-transmitter, the combination 40 with a supporting framework, a driven pulley, and relatively low and high speed driving pulleys mounted coaxially with said driven pulley, of manually controlled means for relatively shifting the driving and 45 driven pulleys into and out of driving relationship including a rocking arm, a pulley-shifting cam carried by said rock-arm, an endwise movable shaft carrying said driven pulley, and a movable fulcrum for the rock- 50 ing arm.
  3. In a power-transmitter, the combination 55 with a supporting framework, a driven pulley, and relatively low and high speed driving pulleys mounted coaxially with said driven pulley, of manually controlled means for relatively shifting the driving and driven pulleys to rotate the latter at correspondingly low and high speeds including a rock-arm, an endwise movable shaft, 60 a movable fulcrum for said rock-arm, and means for shifting the fulcrum of the rock-arm to disengage the driven pulley from both of said driving pulleys.

4. In a power-transmitter, the combination with a supporting framework, a driven pulley, and relatively low and high speed driving pulleys mounted coaxially with said driven pulley, of manually controlled means for relatively shifting the driving and driven pulleys to rotate the latter at correspondingly low and high speeds including a rock-arm, an endwise movable shaft, an operating lever for said rock-arm, a movable fulcrum for said rock-arm, a fulcrum-shifting lever for said rock-arm 70 adapted to be swung into the path of movement of said operating lever whereby the driven pulley is disengaged from both of said driving pulleys and said operating lever is locked against pulley-shifting movement.
5. In a power-transmitter, the combination with a supporting framework, a driven pulley, and relatively low and high speed driving pulleys mounted coaxially with said driven pulley, of an endwise movable shaft, a rock-arm, a rock-shaft, a crank-pin carried by said rock-shaft affording a fulcrum for the rock-arm, an operating-lever for manually actuating the rock-arm to relatively shift the driving and driven pulleys to rotate the latter at correspondingly low and high speeds, and a fulcrum shifting lever carried by said rock-shaft adapted to be swung into the path of movement of said operating lever to thereby disengage the driven pulley from both of said driving pulleys and prevent operation of the operating lever.
6. In a power-transmitter for sewing machines, in combination, a power-transmitting driven pulley operatively connected with said sewing machine, relatively low and high speed driving pulleys, means for relatively shifting said driving and driven pulleys to drive the latter at correspondingly low and high speeds, and means for relatively shifting said driving and driven pulleys to maintain the driven pulley in idle position and render said first mentioned shifting means inoperative.
7. A power transmitter, in combination with a machine adapted to be automatically stopped in a predetermined position, a power transmitting driven pulley operatively connected with said machine, driving pulleys mounted coaxially with and upon opposite sides of said driven pulley, means for relatively shifting the driving and driven pulleys into and out of driving engagement, and means for at will rendering said shifting means inoperative.

In testimony whereof, I have signed my name to this specification.

JOHN S. FINCH.
